Application August 4, 1954, Serial No. 447,758

4 Claims. (Cl. 255—73)

This invention relates to drilling tools and more particularly to tools adapted for use in the releasing of surface casing set in a well bore, or tubing cemented in such a bore, or for similar purposes.

In the drilling of wells and especially in the drilling and production of oil and gas wells, surface casing is usually set and cemented in the upper end of the well bore, such casing providing anchoring means for surface equipment used in carrying out the drilling and producing operations. Such surface casing is frequently of relatively large diameter to permit the introduction of drilling equipment whereby the drilling operations may be carried on through the casing, and the casing usually extends downwardly for several hundred feet from the ground level. The casing is usually cemented in place at the top and bottom by a surrounding body of cement which sometimes extends throughout the entire length of the casing.

A well in which the casing has been set in this manner is often produced by the insertion of a well tubing of smaller diameter than the casing which may also be cemented in place in the casing at one or more locations throughout its length. Due to the fact that the bores of such wells are rarely straight, and because of the relative flexibility of the production string or well tubing, the tubing is usually not concentrically disposed relative to the casing and bore, and may contact the inner wall of the casing and bore at various locations throughout its length.

When a well which has been equipped in this manner is abandoned, the surface casing and tubing is usually left in the well, due to the difficulty of releasing them from the cement, which results in great loss of valuable material.

The present invention has for its chief object the provision of drilling equipment which is adapted to be positioned about the exterior of a pipe set in a well bore, such as a casing or tubing and which may be operated to drill away the surrounding cement to release the casing or tubing whereby the same may be recovered for reuse.

Another object of the invention is to provide drilling equipment of the impact or percussion type embodying a sleeve-like drill adapted to be positioned about the exterior of a casing or tubing and operable to drill away the surrounding layer of cement to release the casing or tubing therefrom.

A further object of the invention is the provision of drilling equipment which may be used in connection with well tubing which has been cemented in a well bore or casing, and which is not concentric with the bore or casing, to drill away the cement and release the tubing without cutting or otherwise damaging the tubing.

Another object of the invention is to provide drilling equipment of the kind referred to embodying means for circulating water or drilling fluid about the exterior of the casing or tubing during the drilling operation to facilitate the action of the drill or to assist in the removal of the drilled material or detritus as the operation proceeds.

2

A still further object of the invention is the provision of drilling equipment constructed for use in the releasing and recovery of well pipe such as casing or tubing which has been cemented in a well bore, which equipment is of simple design and rugged construction capable of long withstanding the hard conditions of use and rough treatment to which such equipment is customarily subjected.

The above and other important objects and advantages of the invention may best be understood from the following detailed description, constituting a specification of the same when considered in conjunction with the annexed drawings, wherein—

Figure 1 is a fragmentary side elevational view illustrating a preferred form of the invention and showing the equipment in use in the releasing of well casing from the bore of a well;

Figure 2 is a cross-sectional view, taken along the line 2—2 of Figure 1, looking in the direction indicated by the arrows;

Figure 3 is a fragmentary, side elevational view partly broken away and partly in cross-section, details of construction of the drill of the invention as illustrated in Figure 1;

Figure 4 is a fragmentary side elevational view of a somewhat different form of the invention, showing the use of the same in the releasing of a tubing string from a well;

Figure 5 is a cross-sectional view taken along the line 5—5 of Figure 4, looking in the direction indicated by the arrows; and

Figure 6 is a cross-sectional view taken along the line 6—6 of Figure 5, looking in the direction indicated by the arrows.

Referring now to the drawings in greater detail the invention is illustrated in Figures 1, 2 and 3 in connection with its use in the releasing of casing from a well whose bore is indicated at O, such casing, designated C, having been set in the bore in the usual manner with or without cementing.

In the present illustration the drilling equipment comprises a drill 10 of the impact or percussion type, which is of generally tubular formation and of a size to fit over the outside of the casing and to pass freely over any couplings or connections therein.

The drill 10 has a lower end portion 12 which is cylindrical and which is provided at its lower end with a blade like edge formed with cutters or teeth 14. The edge portion may have an inner bevelled surface 16 and the teeth 14 may be outwardly flared if desired, to secure efficient cutting action and to guide the drill over any couplings or connections in the casing without cutting or otherwise damaging the same.

Above the cylindrical portion 12 the drill may be cut away along one side to form an upper more or less semi-cylindrical portion 18 which may have a longitudinal groove 20 along its mid portion. The upper end portion of the drill may be provided with tapered edges, one of which is indicated at 22 in Figure 1 to aid in guiding the drill past any external enlargements in the casing such as a coupling or connection.

When the drill is being withdrawn from the well the upper edge portion of the cylindrical portion 12 may also be bevelled, as seen at 13 in Figure 1, for the same purpose.

A tubular stem or circulating pipe 24 is positioned in the groove 20 and secured to the drill in any suitable manner as by welding, this stem extending above the upper end of the drill and being open at its lower end. A pipe 26, which may be in the form of a flexible tube or hose, is attached to the upper end of the tubular stem 24 whereby the drill may be raised and lowered and fluid may be circulated through the stem.

In making use of this form of the invention, the drill,

constructed as described above, is suspended by the pipe 26 for vertical movement and is positioned with the cylindrical portion 12 about a tubular nipple, not shown, attached to the upper end of the casing C as a temporary guide. By successively elevating and dropping the drill, the cement or earth formation surrounding the casing may then be gradually drilled away from around the casing, the drill thus forming an enlarged bore about the casing.

During the drilling operation the bore thus formed may be kept filled or partly filled with water supplied thereto through the pipe 26 and tubular stem 24. If desired water may be circulated downwardly through the stem 24 to pass upwardly about the drill and casing to carry away the cuttings or mud formed.

When a sufficient length of the casing has been thus released from the well bore it may be uncoupled or cut off and removed from the well by the use of any convenient type of conventional equipment provided for that purpose.

A somewhat different form of the drilling equipment of the invention is illustrated in Figures 4, 5 and 6, which is adapted for use in releasing a well tubing which is not in a position concentric with the well bore and which may be in contact with the wall of the bore or the interior of a well casing therein at one or more locations. In Figures 4, 5 and 6, the well bore or casing is indicated at O, within which a well tubing T is positioned, the tubing being out of concentric relation to the bore, whereby the tubing is at certain location closer to or in contact with the interior of the bore or casing. In this form of the equipment the drill 12' is of generally tubular shape and is cut away along one side, as indicated at 18', throughout its length. The opening 18' is of somewhat greater width than the external diameter of the tubing about which the drill is to be positioned, and is preferably provided with inwardly bevelled side edges 22' throughout the length of the opening so that the tubing or any coupling or connection thereon may readily pass through the opening in positioning the drill about the tubing.

The drill 10' is formed with lower end cutters or teeth 14' similar to the teeth 14 of the drill 10 previously described, and has an inwardly bevelled surface 16' which served as a means for grinding the drill past couplings in the tubing. The drill 10' has a longitudinal groove 20' along its mid portion in which a tubular stem 24' is secured in the same manner as in the previously described form of the invention, to which stem a pipe or hose, not shown, may be connected for raising and lowering the drill in the manner previously described.

In making use of this form of the invention, the enlarged bore about the upper end of the tubing may be started with the drill 10 of the form illustrated in Figures 1, 2 and 3, in the manner previously set forth. When the drill 10 reaches a location at which the tubing T is close to or in contact with the wall of the well bore O', however, the lower end of the drill will become wedged between the tubing and the wall of the bore. Upon such wedging action of the drill the operator will know that the drill is engaging the tubing and that there is danger of cutting the tubing by further use of the drill 10. Under these conditions the drill 10 may be withdrawn and the drill 10' placed about the tubing by lowering the drill in the bore, the tubing passing through the opening 18' during such lowering of the drill. By then rotating the drill 10' about the tubing and elevating and dropping the drill at positions where it will not become wedged between the tubing and the wall of the bore, the cement may be drilled away and the tubing released from locations where the tubing is not in concentric relation to the well bore.

After the drill 10' has been thus used to clear a location where the tubing is close to or in contact with the wall of the bore, it may be withdrawn and the drill 10' again used to carry out further drilling where the tubing

is spaced inwardly from the wall of the bore. In this manner substantial lengths of tubing may be released and recovered from the well, without danger of cutting through the tubing at locations where the tubing is close to or in contact with the wall of the bore.

In other respects the drill 10' is operated like the drill 10, water being supplied to the bore through the tubular stem 24' in the same manner as previously described.

It will thus be seen that the invention constructed and operated as described above provides drilling equipment which is economical in construction and efficient in operation and by which valuable well casing or tubing, which would otherwise be lost, may be released and recovered for further use.

While the invention has been disclosed herein in connection with certain specific embodiments of the same, it will be understood that this is intended by way of illustration only, and that numerous changes can be made in the structure and arrangement of the drills without departing from the spirit of the invention or the scope of the appended claims.

Having thus clearly shown and described the invention, what is claimed as new and desired to secure by Letters Patent is:

1. A drilling tool for drilling around a pipe set in a well bore comprising a tubular drill shaped to fit over a pipe in a well bore and to operate against the formation around said pipe, cutters on the lower end of the drill, said drill having an external longitudinal groove terminating above the lower end of the drill and a tubular stem in said groove connected to the drill and whose lower end is open.

2. A drilling tool for drilling around a pipe set in a well bore comprising a drill of generally tubular formation having a cylindrical lower end portion shaped to fit over a pipe in a well bore and to operate against the formation around said pipe and a portion above said cylindrical portion which is arcuate in cross-section, cutters on the lower end of the drill, said lower end portion having an upper inwardly bevelled edge portion positioned to engage an external enlargement on the pipe to guide the drill past said enlargement, said drill having an external longitudinal groove terminating above the lower end of the drill, and a tubular stem in said groove connected to the drill and whose lower end is open.

3. A drilling tool for drilling around a pipe set in a well bore comprising a drill of generally tubular formation having a cylindrical lower end portion shaped to fit over a pipe in a well bore and to operate against the formation around the pipe and an arcuate portion above said cylindrical portion, the lower end of the drill being outwardly flared, cutters on the lower end of the drill, said lower end portion having an upper inwardly bevelled edge portion positioned to engage an external enlargement on the pipe to guide the drill past said enlargement.

4. A drilling tool for drilling around a pipe set in a well bore comprising an elongated drill of arcuate formation in cross-section shaped to partially surround a pipe in a well bore and to operate against the formation around the pipe, said drill having an external longitudinal groove and a tubular stem positioned in said groove and connected to the drill and whose lower end is open.
